UNITED STATES PATENT OFFICE.

W. EVERETT SMITH, OF FRAMINGHAM, MASSACHUSETTS.

DEPURATOR.

SPECIFICATION forming part of Letters Patent No. 375,015, dated December 20, 1887.

Application filed September 4, 1886. Serial No. 212,698. (No model.)

To all whom it may concern:

Be it known that I, W. EVERETT SMITH, of Framingham, in the county of Middlesex, State of Massachusetts, have invented a certain new and useful Improvement in Apparatus for Administering Medicated Vapors by Inhalation, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved cabinet, the door being represented as closed; Fig. 2, a like view, the door being represented as opened, the air-condenser detached, and a portion of the body removed; and Fig. 3, a diagram showing a portion of the inhaling apparatus enlarged.

Like letters of reference indicate corresponding parts in the different figures of the drawings.

My invention relates to that class of apparatus for administering medicated vapors by inhalation in which the patient is placed in an exhausted or partially-exhausted receiver or cabinet; and it consists in certain novel details of construction, as hereinafter more fully set forth and claimed, by which a more effective and otherwise desirable device of this character is produced than is now in ordinary use.

The nature and operation of the improvement will be readily understood by all conversant with such matters from the following explanation.

In the drawings, A represents the body, and B the door, of the cabinet. The body is of sufficient size and suitable form to contain the patient and permit him to be seated comfortably in a chair, C, which is placed therein for that purpose. It is also so constructed as to be substantially air-tight when closed. The door B is hinged to the body at x x, and provided on the outer side with a series of bolts, m, which may be simultaneously operated to fasten it, by means of the crank-plate f and handle z, with which their inner ends are connected. The crank-plate is also connected with a handle, t, on the inner side of the door in such a manner as to enable a patient within

the cabinet to readily open the door when disposed. The door is provided around its edges with rubber or other suitable packing, r, to render it substantially air-tight.

Disposed in the front wall of the body A there is a pane of glass, b, through which the patient may be seen when seated in the chair C, and passing through the center of said pane are two metallic or hard-rubber tubes, D E, 60 said tubes being provided where they pass through the pane with a suitable packing, H, to render the joint air-tight.

A mouth-piece, J, preferably composed of glass, and having two laterally-projecting nipples, d l, is connected with the tubes D E by two flexible rubber pipes, K L, the pipe K connecting the nipple d and the tube D, and the pipe L connecting the nipple l and tube E. The body of the mouth-piece is enlarged to 70 form the chamber g, and provided with a mouth-piece proper, h, and downwardly-projecting nipple i, to which is attached the hollow bulb M, said bulb serving the double purpose of a handle for manipulating the mouth-piece and a receptacle for the condensed spray or vapor from the chamber g. The bulb is detachable to enable it to be emptied when necessary. The outer end of the tube D is preferably provided with a flaring or trumpet-shaped mouth-piece, q. It is also provided with a stop-cock, N, and the pipe L with a stop-cock, O.

Attached to the outer end of the tube E there is a flexible pipe, P, which connects 85 said tube with an ordinary Semple atomizer, R, said atomizer being also connected with an ordinary air-condenser, Q, by a flexible pipe, T, the coupling of which is provided with a stop-cock, y.

An ordinary air-pump, G, is connected with the body A of the cabinet, by means of which the air in said body may be pumped out or exhausted. A tube passes through one of the side walls of the body A, said tube being provided at its inner end with a stop-cock, v, which may be readily opened by the patient in the chair C to admit air into the cabinet. A tube also passes through the front wall of the body A, said tube being provided at its outer end with a stop-cock, w, which may be opened by the physician or a person in attend-

ance on the outer side of the cabinet to admit air to the interior of its body if desired.

In the use of my improvement, the condenser Q being first charged or filled with compressed air, and the stop-cock *y* closed, and the atomizer R filled with medicated liquid, the patient takes his seat in the chair C and the door B is closed and fastened. The stop-cocks O N are then closed and the air in the body A exhausted or partially exhausted by means of the air-pump G, after which the patient inserts the mouth-piece proper, *h*, in his mouth and opens the stop-cock, O. The physician or person in attendance then opens the stop-cocks N *y* and the patient inhales until his lungs are fully inflated. When his lungs are inflated, the patient closes the stop-cock O and exhales the vitiated air through the pipe K and tube D, the closed stop-cock O preventing the air as it is forcibly exhaled from the lungs from passing into the atomizer through the pipe L and tube E. After the air is exhaled, as described, the stop-cock O is again opened and the inhalation repeated.

The medicated vapor from the atomizer as it enters the mouth-piece impinges against the walls of the chamber *g*, thereby causing a portion of the vapor to be condensed or the surplus liquid to be precipitated and to pass into the bulb M, the vapor which thereafter passes through the mouth-piece *h* being comparatively desiccated or dry.

It will be obvious that the pipe K and tube D not only enable the vitiated air from the lungs of the patient to be exhaled without passing through the atomizer, but that it also subserves to admit a quantity of pure air, which is mixed with the medicated vapor in the chamber *g*, at each inspiration of the patient, thereby preventing the sense of strangulation which would be produced by inhaling a heavily-charged vapor unmixed with an independent current of unmedicated air.

In the temporary absence of the physician or attendant the patient may open the door by means of the handle *t*, and in case faintness supervenes he may let air into the cabinet through the stop-cock *v*. When more air is needed in the cabinet at any period during the administration of the vapor, the physician or attendant may open the stop-cock *w*.

It will be obvious that when the stop-cock *y* is opened the air from the condenser Q will pass into the atomizer R and vaporize the

medicated liquid contained therein, the medicated vapor thus produced being constantly blown through the pipe P, tube E, and pipe L into the mouth-piece J until said stop-cock is closed.

I do not confine myself to the use of any special form of air-condenser, air-pump, or atomizer, as any devices adapted to suitably perform the functions of these respective parts of the apparatus may be employed.

Having thus explained my invention, what I claim is—

1. In an apparatus for inhaling and exhaling medicated vapors and atmospheric air, either separately or in a mixed condition, a mouth-piece having a chamber in which the vapor and air are mixed on their passage, in combination with a pipe for conducting vapor to said chamber, a pipe for conducting air to and from said chamber, and a stop-cock for closing said air-pipe, said mouth-piece being provided with an opening through which the mixed air and vapor may pass from said chamber into the mouth of the patient, an opening through which air may enter said chamber from said air-pipe, and an opening through which vapor may enter said chamber from said vapor-pipe, substantially as described.

2. In an apparatus for inhaling and exhaling medicated vapors and atmospheric air, either separately or in a mixed condition, an air-tight cabinet, a pump for exhausting air therefrom, and a mouth-piece having a chamber in which the vapor and air are mixed on their passage, in combination with a pipe for conducting vapor to said chamber, a pipe for conducting air to and from said chamber, and a stop-cock for closing said air-pipe, said mouth-piece being provided with an opening through which the mixed air and vapor may pass from said chamber into the mouth of the patient, an opening through which air may enter said chamber from said air-pipe, and an opening through which vapor may enter said chamber from said vapor-pipe, substantially as described.

3. The mouth-piece J, having the chamber *g* and provided with the nipples *d l i*, in combination with the bulb or handle M, substantially as described.

W. EVERETT SMITH.
